UNITED STATES PATENT OFFICE

WILLIAM V. DERBY, OF BALTIMORE, MARYLAND, ASSIGNOR TO THE CROWN CORK AND SEAL COMPANY OF BALTIMORE CITY, A CORPORATION OF MARYLAND.

PACKAGING APPARATUS.

1,418,631.

Specification of Letters Patent. Patented June 6, 1922.

Application filed December 11, 1919. Serial No. 344,255.

To all whom it may concern:

Be it known that I, WILLIAM V. DERBY, a citizen of the United States, residing at Baltimore, and State of Maryland, have invented certain new and useful Improvements in Packaging Apparatus, fully described and represented in the following specification and the accompanying drawings, forming a part of the same.

10 This invention relates to packaging apparatus and particularly to bottle feeding mechanism of the type in which bottles are fed into the embrace of pockets which center the bottles for the packaging operation.

15 It is the principle object of the invention to provide bottle feeding mechanism such that bottles may be positioned for the packaging operation with a higher degree of certainty than has heretofore been possible and 20 with a minimum amount of breakage and a minimum agitation of the bottles.

With this general object and other objects and advantages obvious to those skilled in the art in view, the invention consists in the features, details of construction and combinations which will be first described in connection with the accompanying drawings and then more particularly pointed out.

In the drawings—

30 Figure 1 is a top plan view, with parts in section, of a bottle feeding mechanism constructed in accordance with the invention;

Figure 2 is a sectional view taken on the broken line 2—2 of Fig. 1;

35 Figure 3 is a similar view taken on the line 3—3 of Fig. 2;

Figure 4 is a similar view, taken on the line 4—4 of Figure 2;

Figure 5 is a similar view taken on the 40 line 5—5 of Fig. 4; and

Figure 6 is a view, in end elevation, taken in the direction of the arrow 6 in Fig. 4.

The feeding mechanism illustrated is designed for use with packaging apparatus of the type in which bottles are positioned one after another beneath a single packaging mechanism, although it will be understood that the invention is not necessarily limited to such type of apparatus. Referring to the 45 drawings in the embodiment shown as an example, beneath the packaging mechanism, such as a capping head (conventionally illustrated at 9) is a stationary supporting table 10. Rotating above this table is a bottle 50 centering spider 11 having a plurality of

spaced bottle receiving pockets 12. The spider 11 is mounted on a vertical shaft 13 by means of dowels 14 on a collar on the shaft. Means is provided for rotating the spider shaft 13 for example, with an intermittent movement. Although capable of various constructions, in the present embodiment, on the lower end of shaft 13, a ratchet 15, having equally spaced notches, is mounted by means of a friction cone 16 and friction collar 17. The latter members are held tight by means of a nut 17' on the top end of the shaft. By loosening this nut, the friction cone and collar are released so that the spider may be angularly adjusted with relation to the ratchet.

The ratchet is driven by a pawl 18 mounted on a carrier 19 and held to its duty by a spring 20. This carrier is pinned to a link 21 connected to a crank arm 22 which is mounted on a vertical shaft 23. This shaft is driven by means of a gear 24 mounted thereon and meshing with a pinion 25 on a stud 26. Also mounted on the latter is a gear 27 meshing with a pinion 28 connected with a bevel gear 29 which meshes with a bevel pinion 30 on a shaft 31. This shaft is driven, in turn, by timing gears 32 and 33 from a main drive shaft 34 to which power may be applied in any suitable manner. In complete packaging apparatus, the shaft 31 will preferably have such connection with the capping head that there will be proper synchronization between the head and the bottle centering spider.

Through the medium of the mechanism described, the spider 11 is given an intermittent rotary movement at timed intervals. To equalize this angular movement of the spider, means is provided for locking the ratchet at the end of a given stroke. To this end, in the present embodiment, there is provided a locking pawl 35, pressed toward the ratchet by a spring 36. As the ratchet makes its forward stroke, the pawl 35 drops into a notch to lock the ratchet against further movement. To dislodge the locking pawl to free the ratchet for its next forward stroke, the carrier 19 carries a cam plate 37 which dislodges pawl 35 on the back stroke of the carrier.

Means is provided for transporting the bottles from a point of delivery toward the spider 11. As will hereinafter be more fully explained, the bottles during this trans-

90

65

60

55

50

portion, may be indiscriminately arranged, this movement placing them where they may be positioned and spaced for accurate feeding into the embrace of the spider pockets. 5 Although the transportation means is capable of various constructions, in the embodiment illustrated, flush with the supporting table 10 is a rotary table 40. This table is driven in the direction of the arrow (Fig. 1) 10 by means of a shaft 41 to which it is secured and which is journaled in suitable bearings carried by the frame 42. On shaft 41 is a worm wheel 43 meshing with a similar gear 44 on a shaft 45 which is driven from 15 the main drive shaft 34 by spiral gears 47, 48.

Bottles are delivered to the rotary table 40 in any suitable manner, and in indiscriminate arrangement. As they are carried around toward the spider, they are guided in a proper path, in the exemplification illustrated, by an outer guide member 50 extending about a portion of the edge of the table, and an inner and concentric guide member 52. The outer guide is carried by brackets 51 and the inner guide by a bracket 53. As appears in Fig. 1, both guide members terminate in straight portions for directing the bottles from the rotary table 30 onto the stationary table 10.

There is provided means for positioning the bottles presented as just described, in a given position and means dependent on the presence of a bottle in such position for 35 moving the bottle into the embrace of a spider pocket. This may be accomplished, for example, by an abutment into contact with which the bottles are moved, for positioning the same, and a normally inoperative angularly movable bottle sweeper which is rendered operative by the movement of a bottle into engagement with the abutment. Although variable within a wide range, the bottle sweeper may be operable only when 40 in a given angular position and it may be moved into such position by the advance of a bottle into the position referred to. In the embodiment here shown as an example, there is provided a bottle positioning device 45 in the form of an abutment 55 which is located, as appears in Fig. 1, transverse the path of the advancing bottles. Each bottle moved forward by the rotating table is brought into engagement with the abutment 50 55 and is thus located in a given position for being fed to the centering pockets. The bottle positioned by the abutment is moved into the embrace of one of the pockets by an angularly movable bottle sweeper. In 60 the exemplification here illustrated, there is provided a double decked rotary bottle sweeper 56 having a plurality of bottle engaging arms 57 of the reverse curve form shown in Fig. 1, the two sweeper plates passing, respectively, over and under the abut-

ment as the sweeper rotates. The sweeper is secured, in any suitable manner, to a shaft 58 freely rotatable in bearings 59 on frame 42. It is given an intermittent rotation, under the conditions to be described, by means 70 of a pawl and ratchet. As here shown as an example, secured to the shaft 58 is a ratchet 60 having a number of spaced notches 61 equal to the number of sweeper arms 57. Cooperating with the ratchet 75 notches is a driving pawl 62 pinned to an oscillating carrier 63, the pawl being held to its duty by a spring 62'. As hereinafter described, during the operation of the machine, the pawl has a reciprocating stroke 80 tending to operate the ratchet. Movement of the ratchet takes place, however, only when the latter is in a given angular relation with the pawl and it is placed in such relation by the movement of a bottle into 85 the given position above referred to. It will be seen that the ratchet can be driven forward only when one of the notches is within reach of the pawl on its driving stroke. Should the ratchet be positioned, as 90 in Fig. 1, with a notch just out of reach of the pawl, the pawl will make its stroke without driving the ratchet. The parts are so arranged that when a ratchet notch is in 95 operative relation with the pawl, there is no sweeper arm between the abutment and the advancing bottle, and when a notch is out of reach of the pawl, as in Fig. 1, the corresponding sweeper arm is slightly in advance of the abutment, or, in other words, 100 between the abutment and the advancing bottles. In order that the ratchet notch may be placed within reach of the pawl, the ratchet must be given a slight angular movement. This movement in the present embodiment, is caused by the advance of a bottle into contact with the abutment. It will be seen from Fig. 1, that a bottle, in moving up against the abutment, pushes ahead of it the arm of the freely movable 105 sweeper. This movement of the sweeper moves the ratchet 60 sufficiently to bring a notch within reach of the drive pawl. Thus, the bottle sweeper operation depends on the proper positioning of a bottle to be fed. 110

Means is provided for operating the drive pawl in synchronism with the movement of the bottle receiving pockets of the spider. Although capable of various constructions, as shown, the oscillating pawl carrier 63 is 115 pinned to a link 64 connected to a crank arm 65 on the shaft 23. As the crank arm 65 which drives the sweeper and the crank arm 22 which drives the spider are on the same shaft, the spider and sweeper are rotated in 120 proper synchronism.

Means is provided for positioning the sweeper ratchet in the non-operative relation with the pawl above described, that is to say, with a notch out of reach of the 125 130

pawl. In the present exemplification, this is accomplished by a spring pressed positioning pawl 66 located to drop into a notch 61 on the forward stroke of the ratchet and 5 stop the latter in the non-operative position referred to.

Means is also provided for removing this locking pawl, so that the sweeper, now positioned for displacement by the next bottle, 10 may be freely movable. As here shown, as an example, this is accomplished by a cam plate 67 on the oscillating carrier 63. As the latter makes its back stroke, the cam 67 dislodges the pawl 66, as appears in Fig. 4, 15 the cam being designed to hold the pawl away from the ratchet until the pawl completes its next stroke and the ratchet is ready to be again locked.

In the operation of the parts thus far 20 described, assuming the parts to be in the position of Fig. 1 with a ratchet notch 61 out of reach of the pawl 62, one of the sweeper arms will be slightly in advance of the abutment. Rotation of the main drive shaft 25 causes a continuous rotation of table 40, an intermittent rotation of the centering spider and a reciprocation of the pawl 62. Bottles being fed to the rotary table 40 are carried, indiscriminately spaced, and guided in a 30 proper path, toward the abutment. As long as no bottle is present in feeding position adjacent the abutment, the sweeper remains inoperative because the pawl 62 cannot reach the notch of the ratchet 60. When, however, 35 a bottle moves into engagement with the abutment, this movement causes angular displacement of the sweeper sufficient to place the ratchet notch within reach of the pawl. On the pawl's next stroke, therefore, the 40 pawl drives the ratchet, thus rotating the sweeper which moves the positioned bottle into the embrace of a spider pocket. At the end of the feeding stroke of the sweeper, the positioning pawl 66 drops into a ratchet 45 notch, so as to stop the ratchet in its non-operative position with the next arm ready to be moved by an approaching bottle. On the return stroke of the pawl carrier 63, the cam 67 dislodges the positioning pawl 66 to 50 leave the sweeper freely movable as originally. In the present embodiment, the parts are so related that the spider is stationary during the movement of the sweeper and starts forward at substantially the instant 55 a bottle is placed in one of the pockets by the sweeper, although other arrangements are possible. In any event, due to the construction before described, the movements of sweeper and spider are properly timed, and 60 the sweeper operates only when a bottle is in a proper position to be fed. As a result, the feeding of the bottles to the pockets is accurate and with little or no agitation.

Means is provided for damping the movement of the feeding bottles. To this end, in

the present embodiment, located in the path of the bottles is a comparatively stiff leaf spring 70 carried in the end of guide members 50. This damping spring prevents excessive impact of the bottles as they 70 are fed into the spider pockets, and also prevents bottles getting into the spider pockets by accident.

Means is also provided for guiding and 75 steadyng the bottles being fed. As here shown, as an example, formed integral with the abutment 55 is a guiding and steadyng member 71 located substantially tangential to the centering bottles. In order that the abutment and the member 71 may have their 80 positions adjusted, the arm 72 on which they are carried is slotted, as appears in Fig. 1. The slot rides on a pin 73, having a lock nut 74. By loosening the latter, the arm 72 may be shifted to adjust the abutment and 85 guide.

It will be seen that after a bottle has been fed to one of the spider pockets, subsequent 90 rotation of the spider carries the bottle around to packaging position beneath the head 9, as shown by the bottle 75. There is provided means for centering and holding 95 the bottles in the pockets in this packaging position. This may be accomplished, for example, by a yielding device for pressing the bottles toward the back of the pockets. Although capable of various constructions, in the form shown, located tangential to the bottles when in packaging position, is a 100 centering and holding guide 76 carried on the end of a pin 77 which is slidable in a sleeve 78 adjustably mounted in a bracket 79. The pin 77 is normally pressed toward the spider by a spring 77', the outward movement being limited by collar 80. The guide member 76 and the pin are prevented from turning by sliding pins 81.

The comparatively slight pressure of 110 spring 77' acting through guide member 76, serves to center the bottle and hold it securely in packaging position. In case bottles are presented that are slightly larger than normal, this is compensated for by the yielding of the guide member against its spring.

To remove the bottles following the operation of the packaging mechanism, various 115 suitable means may be employed. As here illustrated, flush with the stationary table 10 is a second rotary table 83. This table 120 is mounted on a shaft 84 rotated by means of a worm gear 85 meshing with a worm 86 on shaft 45. Located above the table are two guide members 87 and 88. As the successive movements of the spider carry the bottles away from immediate packaging position, they are directed onto the table 83 by 125 guide 88 and are carried around in the direction of the arrow, Fig. 1, between the guides. These guides terminate in straight 130

portions, which direct the bottles from the rotary table onto the stationary table 10 again, at a point where they may be removed. The table 83 rotates at such speed that a bottle taken thereby is removed from the reach of the next bottle delivered by the spider.

It is to be understood that the term "bottles" is used in its comprehensive sense to include any suitable receptacle.

What is claimed is:

1. In a packaging apparatus, and in combination, a bottle centering spider having a plurality of bottle receiving pockets, means for rotating said spider, a bottle sweeper for feeding the bottles into said pockets, and means operating in synchronism with said spider-rotating means and tending to operate said sweeper to feed a bottle, the sweeper being operated thereby only when in given relation with said operating means and being placed in such relation by the movement of a bottle into a position to be fed.

2. In a packaging apparatus, and in combination, a bottle centering spider having a plurality of bottle receiving pockets, means for rotating said spider, a conveyor means for conveying bottles toward said spider, an abutment in the path of the conveyed bottles, a bottle sweeper for feeding the bottles into said pockets, and means operating in synchronism with said spider-rotating means and tending to operate said sweeper to feed a bottle, the sweeper being operated thereby only when in given relation with said operating means and being placed in said relation by the movement of a bottle into engagement with said abutment.

3. In a packaging apparatus, and in combination, a bottle centering spider having a plurality of bottle receiving pockets, means for rotating said spider, a bottle sweeper for feeding the bottles into said pockets, and means operating in synchronism with said spider-rotating means and tending to operate said sweeper to feed a bottle, the sweeper being operated thereby only when in given relation with said operating means and arranged to be in such given relation when a bottle is in position to be fed.

4. In a packaging apparatus, and in combination, a bottle centering spider having a plurality of bottle receiving pockets, means for giving the spider an intermittent rotation, a freely rotatable sweeper for feeding bottles into the embrace of said pockets, and means tending to rotate the sweeper and operative only when said sweeper is in a given angular position.

5. In a packaging apparatus, and in combination, a bottle centering spider having a plurality of bottle receiving pockets, means for giving the spider an intermittent rotation, a freely rotatable sweeper for feeding bottles into the embrace of said pockets,

means tending to rotate said sweeper, and operative only when the sweeper is in a given angular position, and means whereby the movement of a bottle into proper position to be fed causes said sweeper to take 70 said given position to render the rotating means operative.

6. In a packaging apparatus, and in combination, a bottle centering spider having a plurality of bottle receiving pockets, means 75 for giving the spider an intermittent rotation, a freely rotatable sweeper for feeding bottles into the embrace of said pockets, means for rotating said sweeper when the latter is in a given angular position, means 80 for positioning the sweeper in non-operative position, and an abutment toward which the bottles to be fed are moved, the movement of a bottle into engagement with said abutment serving to move the sweeper into said 85 given position to render the rotating means operative.

7. In a packaging apparatus, and in combination, a bottle centering spider having a plurality of bottle receiving pockets, means 90 for giving the spider an intermittent rotation, an abutment toward which bottles to be fed are moved, a rotary sweeper having a plurality of bottle engaging arms for feeding bottles into the embrace of said pockets, 95 said sweeper being freely rotatable whereby it may be positioned with one of its arms between the abutment and the advancing bottles, and means tending to rotate said sweeper, and operative only when none of 100 said arms is between the abutment and the advancing bottles.

8. In a packaging apparatus, and in combination, a bottle centering spider having a plurality of bottle receiving pockets, means 105 for giving the spider an intermittent rotation, an abutment toward which bottles to be fed are moved, a freely rotatable sweeper having a plurality of bottle engaging arms for feeding the bottles into the embrace of 110 said pockets, means tending to rotate said sweeper, and operative only when none of said arms is between the abutment and the advancing bottles, and means for positioning the sweeper with one of its arms between 115 the abutment and the advancing bottles.

9. In a packaging apparatus, and in combination, a bottle centering spider having a plurality of bottle receiving pockets, means for giving the spider intermittent equal 120 angular movements, a positioning abutment, means for transporting bottles toward said abutment, a freely rotatable sweeper for feeding bottles, positioned by said abutment, into the embrace of said pockets, and means 125 operating in synchronism with the movement of said pockets tending to rotate said sweeper, and being operative only when the sweeper is in a given angular position, the movement of a bottle into engagement with 130

said abutment causing the sweeper to take said given position to render the rotating means operative.

10. In a packaging apparatus, and in combination, a bottle centering spider having a plurality of bottle receiving pockets, means for giving the spider intermittent equal angular movements, a positioning abutment, means for transporting bottles toward said abutment, a freely rotatable sweeper for feeding bottles positioned by said abutment into the embrace of said pockets, means operating in synchronism with the movement of said pockets tending to rotate said sweeper and being operative only when the sweeper has a given angular position, and means for causing the sweeper to take a non-operative position, the movement of a bottle into engagement with said abutment causing the sweeper to move into said given position to render the rotating means operative.

11. In a packaging apparatus, and in combination, a bottle centering spider having a plurality of bottle receiving pockets, means for giving the spider an intermittent rotation, an abutment toward which bottles to be fed are moved, a rotary sweeper having a plurality of bottle engaging arms for feeding bottles into the embrace of said pockets, a ratchet moving with said sweeper and having a number of notches equal to the number of sweeper arms, a pawl for engaging said notches to rotate the ratchet and means for reciprocating said pawl, said sweeper and ratchet being freely rotatable whereby they may be positioned with one of said arms between the abutment and the advancing bottles and the corresponding ratchet notch out of reach of said pawl, the movement of a bottle into engagement with the abutment serving to cause displacement of the sweeper to place a notch within reach of the pawl.

12. In a packaging apparatus, and in combination, a bottle centering spider having a plurality of bottle receiving pockets, means for giving the spider intermittent rotation, an abutment toward which the bottles to be fed are moved, a freely rotatable sweeper having a plurality of bottle engaging arms for feeding bottles into the embrace of said pockets, a ratchet having a number of notches equal to the number of said arms and moving with said sweeper, a pawl for engaging said notches to rotate the ratchet and sweeper, means for reciprocating said pawl, and means for positioning the ratchet with no notch within reach of said pawl, the sweeper in this position of the ratchet having an arm between the abutment and the advancing bottles, the movement of a bottle into engagement with the abutment serving to move the sweeper to bring a ratchet notch within reach of the pawl.

13. In a packaging apparatus and in combination, a bottle centering spider having a

plurality of bottle receiving pockets, means for rotating the spider, a conveyor means for conveying bottles toward the spider, a positioning abutment in the path of the bottles, a freely rotatable sweeper for feeding bottles into the pockets, and means operating in synchronism with the movement of said pockets and tending to rotate said sweeper, and operative only when the sweeper is in a given angular position, the sweeper being placed in such angular position by the movement of a bottle into engagement with said abutment.

14. In a packaging apparatus, and in combination, a bottle centering spider having a plurality of bottle receiving pockets, means for rotating said spider, an abutment toward which bottles to be fed are moved, a freely rotatable sweeper having a plurality of bottle engaging arms for feeding bottles into said pockets, means tending to rotate said sweeper and operative only when none of said arms is between the abutment and the advancing bottles, means for stopping the sweeper, during its rotation, with one of its arms between the abutment and the advancing bottles, and means for removing said stopping means.

15. In a packaging apparatus, and in combination, a bottle centering spider having a plurality of bottle receiving pockets, means for rotating said spider, an abutment toward which bottles to be fed are moved, a rotary sweeper having a plurality of bottle engaging arms for feeding bottles into said pockets, a ratchet moving with said sweeper and having a number of notches equal to the number of sweeper arms, a pawl for engaging said notches to rotate the ratchet, means for reciprocating said pawl, a stop pawl for positioning the sweeper and ratchet and so that one of the sweeper arms is between the abutment and the advancing bottles and the corresponding notch out of reach of the operating pawl, and means for removing said stop pawl so that the sweeper and ratchet may be moved into operative relation with the operating pawl by the movement of a bottle into engagement with the abutment.

16. In a packaging apparatus and in combination, a bottle centering spider having a plurality of bottle receiving pockets, means for giving the spider an intermittent rotation, an abutment toward which bottles to be fed are moved, a freely rotatable bottle sweeper for feeding bottles into said pockets, means tending to rotate said sweeper and operable only when the sweeper is in a given angular position, the sweeper being placed in such position by the movement of a bottle into engagement with said abutment, the spider rotating means and the sweeper rotating means being so synchronized that the spider is stationary during the feeding movements of the sweeper.

17. In a packaging apparatus, and in com-

bination, a packaging mechanism, a bottle centering spider having a plurality of bottle receiving pockets, means for giving said spider an intermittent rotation, means for feeding bottles into said pockets, a bracket adjacent the packaging mechanism, a spring-pressed pin slidable in said bracket, a bottle guide on said pin and substantially tangential to a bottle in packaging position, a plurality of pins on said bottle guide and slid-

ing in said bracket, and a head in said first named pin for limiting the movement of the guide toward the spider.

In testimony whereof, I have hereunto set my hand.

WILLIAM V. DERBY.
